Primary Examiner — Samantha Q Lawrence*(74) Attorney, Agent, or Firm* — Manabu Kanesaka(57) **CLAIM**

The ornamental design for a connector, as shown and described.

DESCRIPTION

FIG. 1 is a front elevational view of a connector showing our new design;
 FIG. 2 is a rear elevational view thereof;
 FIG. 3 is a right side elevational view thereof;
 FIG. 4 is a left side elevational view thereof;
 FIG. 5 is a top plan view thereof;
 FIG. 6 is a bottom plan view thereof;
 FIG. 7 is a perspective view showing a front, top and right side thereof;
 FIG. 8 is a perspective view showing a rear, bottom and left side thereof;
 FIG. 9 is a perspective view showing a front, right and bottom side thereof; and,
 FIG. 10 is a perspective view showing a rear, left and top side thereof.
 The broken line showing of the connector is for the purpose of illustrating portions of the article and forms no part of the claimed design.

1 Claim, 8 Drawing Sheets(56)
